Specification for Design.

Patented Aug. 31, 1920.

Application filed February 21, 1919. Serial No. 278,547. Term of patent 7 years.

To all whom it may concern:

Be it known that I, GEORGE E. STIMPSON, a citizen of the United States, residing at Worcester, in the county of Worcester and State of Massachusetts, have invented a new, original, and ornamental Design for an Auxiliary Desk-Top, of which the following is a specification, reference being had to the accompanying drawing, forming part of

this specification, in which the figure is a perspective view of an auxiliary desk top.

I claim:—

The ornamental design for an auxiliary desk top as shown.

In testimony whereof I have hereunto affixed my signature.

GEORGE E. STIMPSON.
